UNITED STATES PATENT OFFICE

GEORGE FEDDEN, OF NEW YORK, N. Y.

DESIGN FOR A STOCKING

Application filed May 2, 1928. Serial No. 26,545. Term of patent 14 years.

To all whom it may concern:

Be it known that I, GEORGE FEDDEN, a citizen of the United States, residing at the city of New York, borough of the Bronx, Bronx County, in the State of New York, have invented a new, original, and ornamental Design for a Stocking, of which the following is a specification, reference being had to the accompanying drawings, forming a part thereof.

In the drawings—

Figure 1 is a side elevation of a stocking showing my said design; the stocking being shown partly folded or lapped, and

Fig. 2 is an enlarged detail face view of a portion of the stocking illustrated at Fig. 1, and showing a portion of the annular band on an enlarged scale.

I claim:

The ornamental design for a stocking, as shown and described.

GEORGE FEDDEN.
